UNITED STATES PATENT OFFICE.

HERMANN STELZNER, OF LUBECK, GERMANY, ASSIGNOR TO ALEXANDER BERNHARD DRÄGER, OF LUBECK, GERMANY; ELFRIEDE DRÄGER, NÉE STANGEN, EXECUTRIX OF SAID DRÄGER, DECEASED.

DIVING EQUIPMENT.

Application filed September 27, 1927; Serial No. 222,274, and in Germany October 11, 1926.

For what may be termed dressless diving equipment, as distinct from diving suits with their appurtenances, small breathing apparatus or applicances are used comprising an air-generator usually carried on the chest and a breathing bag located on the back at the height of the shoulders.

It has been found that there is some inconvenience in the use of this kind of equipment inasmuch as searching on the ground is impeded on account of the fact that the buoyancy of the apparatus attached to the upper part of the body of the diver, particularly the breathing bag, makes it difficult to walk about in a stooping position as is occasioned in searching, and which is necessary for the purpose of looking on the ground with the eyes close to the feet. The reason why the buoyancy impedes such stooping will be well understood, particularly in consideration of the influence of the breathing bag, when it is taken into account that as soon as the diver, who is only burdened by weights on his legs, bends his body down, the buoyancy of the breathing bag will act with a leverage which corresponds substantially to the length of the upper part of the body, the fulcrum lying on the loins of the diver. The diver thus can only effect a bending of the upper part of his body, while at the same time overcoming the moment of the thrust due to the buoyancy of the breathing apparatus. Even when the weights serving for burdening are not only arranged on the legs, but also on the rim of the diver's jacket, the force distribution is not materially changed.

The object of the present invention is to overcome this difficulty, to facilitate the work of searching and also to reduce the burden of the weights on the legs and therefore also the muscular effort required in moving them. This task is solved by employing a sinker weight which is evenly distributed at the height of the shoulders, preferably in the shape of a wreath or necklace hanging round the neck of the diver. In some arrangements according to the invention other heavy strips, for instance, strips of lead, may be used on the seams of the breathing bag to counteract the thrust due to the buoyance of the same.

These strips alone, however, are not sufficient, for though they would overcome the buoyance of the breathing bag, it would still be difficult to walk about in an inclined posi-

tion because of the thrust due to the buoyancy of the upper part of the body, which would still act with the leverage named together with the thrust due to the other parts of the breathing apparatus located on the chest. If however, this direct burdening of the breathing bag is used together with the wreathlike or necklace-like weight the latter may be made correspondingly lighter so that it hangs more conveniently. In any case when making use of the invention the weights on the feet, having, for instance, the shape of the usual iron sandals may be reduced to such an extent that they are only heavy enough to overcome the buoyancy of the legs, so that the diver can walk about without special exertions of the muscles of the legs, which will give a further advantage.

In the accompanying drawing an arrangement according to the invention is shown by way of example.

Figure 1 is a view of the diving equipment applied to a diver, and

Figure 2 is a detail showing the breathing bag.

The diving apparatus consists by way of example of an air regenerator *a* (comprising for instance a potash-cartridge and oxygen cylinder), the breathing bag *b* and the breathing hose *c*. In other respect the construction of the equipment is optional and known and need therefore not be described in detail. The arrow *A* signifies the direction of the thrust due to the buoyancy created by the breathing bag *b*, which as is evident as soon as the diver inclines towards the front, acts on a leverage the length of which corresponds to that of the upper part of the body and the fulcrum lying at or in the vicinity of the loins. A similar though correspondingly smaller buoyancy acts with this leverage at the height of the chest. In order to counteract both buoyancies, according to the present invention, a wreath or necklace of weights *d* is used, which is slipped over the head and consists of a heavy chain or of a leather hose filled with lead balls; the direction of the force due to the weight of this chain or the like, acting evenly on the shoulders and bearing on the breathing bag as well as on the front part of the breathing apparatus and counteracting the buoyancy, is indicated by the arrow *B*. The thrust to be overcome and thus also of the weight of the

chain depends on the total buoyancy of the diver and on the sum of the buoyancies of two parts of the breathing apparatus. The former depends on the weight of the sandals *f*, which in this case need only be made so heavy, that the buoyancy of the legs is balanced, while the remaining buoyancy is balanced by the chain *d*. If the latter is to be reduced as to its weight, so as not to press too hard, it is advisable to provide the breathing bag *b* with lead strips *g* on the seams, as is shown in Figure 2.

It is evident, that by adapting the method of burdening or weighting as set forth the buoyancy thrusts on walking in stooped position are balanced directly at the place where they act by a thrust having the same leverage, that is to say by a thrust acting at the height of the shoulders, so that an inclination of the body towards the front will entail no effort by the diver to overcome the increased moment of the upward thrust due to the

buoyancy of the breathing bag and the other elements mentioned above.

I claim:

1. In a dressless diving equipment, the combination with a breathing apparatus arranged to be positioned about the back and chest of the diver, of a weighting element adapted to be worn by said diver so as to act at approximately the height of the shoulders to overcome the buoyancy of said apparatus when said diver is in stooping position.

2. In a dressless diving equipment, the combination with a breathing apparatus arranged to be positioned about the back and chest of the diver, of a weighted necklace adapted to be worn by said diver so as to act at approximately the height of the shoulders to overcome the buoyancy of said apparatus when said diver is in stooping position.

In testimony whereof I have signed my name to this specification.

HERMANN STELZNER.
